UNITED STATES PATENT OFFICE

98,908

DESIGN FOR ELECTRIC LAMP

Norman Bel Geddes, New York, N. Y., assignor to
Revere Copper and Brass Incorporated, Rome,
N. Y., a corporation of Maryland

Application February 13, 1935, Serial No. 55,393

Term of patent 7 years

To all whom it may concern:

Be it known that I, Normal Bel Geddes, a citizen of the United States and a resident of the city, county, and State of New York, have invented a new, original and ornamental Design for Electric Lamps, of which the following is a specification, reference being had to the accompanying drawing, forming part thereof.

In the drawing:—

Fig. 1 is a side elevation of an electric lamp, showing my new design; and

Fig. 2 is a perspective according to Fig. 1 with the shade tilted into a different position.

The stippling in the drawing indicates surface shading.

I claim:—

The ornamental design for an electric lamp, substantially as shown and described.

NORMAN BEL GEDDES.
